(57) **CLAIM**

The ornamental design for a comb, as shown and described.

DESCRIPTION

FIG. 1 is a top, rear and left side perspective view of a comb, as showing my new design;

FIG. 2 is a bottom, front and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged top plan view of the comb; and,

FIG. 10 is an enlarged bottom plan view of the comb. The broken lines in the drawings depict portions of the comb that form no part of the claimed design.
